UNITED STATES PATENT OFFICE

2,530,128

FUEL INJECTOR

William H. Mashinter, Chicago, Ill.

Application May 29, 1944, Serial No. 537,793

22 Claims. (Cl. 103—148)

1

This invention pertains to pump mechanism, injector mechanism or atomizing mechanism adapted to either supply solid liquid or spray comminuted fluid, or mixtures of fluid and solid.

Fuel injection pumps as heretofore designed commonly include a plunger working in a cylinder and intermittently actuated to deliver measured quantities of fuel to the engine. Because of the high fuel pressures ordinarily involved, a very close fit between plunger and cylinder is required for successful operation and a leak-proof fit is extremely difficult to obtain and impossible to maintain, particularly when using light fuels, such as gasoline, having little or no lubricating properties.

One object of the present invention is to provide a substantially leak-proof fuel injection pump.

Another object is to provide a fuel injection pump that is substantially immune to leakage producing wear.

Another object is to provide an improved bellows type of pump capable of withstanding high pressures over long periods of use.

Another object is to combine a bellows type of pump and a fuel injection nozzle into a unitary structure.

Another object is to provide a fuel injection nozzle having a self-contained bellows type of pump and a loaded discharge valve responsive to the pressure in the pump.

Another object is to provide a pump having a pressure responsive discharge valve so arranged as to be mechanically operated in the event of failure in pump pressure.

Another object is to provide a pump fed fuel injection nozzle having a self-cleaning discharge valve.

Another object is to provide a combined fuel pump and injection nozzle of improved, simple and inexpensive design.

Another object of the invention is to provide pump mechanism so constructed and arranged that it may be used to pump solid liquid.

Another object of the invention is to provide a pump for supplying fluid under pressure and in measured quantities to means for utilizing the supplied fluid, as where fuel is sprayed into the cylinder of an engine or where other liquid, such as water, is sprayed into such cylinder for power or anti-detonating reasons.

Another object of the invention is to provide a readily controllable injector adapted to supply selected quantities of fluid, as fuel, to the cylinder of an engine, and wherein means is pro-

2

vided to eliminate air or gas from the fluid prior to injection.

Another object is to provide injector or pump mechanism for supplying fuel to a cylinder of an internal combustion engine which may be adapted to be driven by a cam shaft of the engine, by means operable from an adjacent cylinder, by means operable by the cylinder itself, by compression or vacuum means, by vacuum from the cylinder itself or by electrically operated means.

Another object is to provide injecting means for supplying fuel to an internal combustion engine which may be used with manifold or separate cylinder injection and wherein the fuel is introduced in properly atomized condition over the entire range of operation of the engine, i. e. regardless of the operating speed of the engine.

Another object of the invention is to provide an injector for supplying fuel to an internal combustion engine, wherein a balanced diaphragm is used as the fuel pumping means.

Another object is to provide injecting means wherein the amount of fluid supplied therefrom is controlled by the pressure of the fluid delivered to the injecting means.

With these and various other objects in view, the invention may consist of certain novel features of construction and operation as will be more fully described and particularly pointed out in the specification, drawings and claims appended hereto.

In the drawings, which illustrate embodiments of the device and wherein like reference characters are used to designate like parts—

Figure 11 is a schematic diagram showing the crank position of the pistons of the engine illustrated in Figure 10;

Figure 12 is a fragmentary sectional elevation showing a control valve for the injector, said valve being shown in the adjacent cylinder;

Figure 13 is a sectional elevation of a modified form of injection system wherein the injector may be operated by the suction from the cylinder supplied by the fuel therefrom, or operated by an adjacent cylinder, or wherein the injector may supply fuel to an intake manifold;

Figure 14 is a diagrammatic view of a modified form of injection system wherein the amount of fuel injected into a cylinder or intake manifold is controlled by the pressure of the fuel delivered to the injector.

This application is a continuation-in-part of application Serial No. 433,930, filed March 9, 1942, now abandoned.

The injection nozzle illustrated in Figures 1 to 3, comprises a hollow head 10 seated against and closing the lower open end of a substantially cylindrical housing 11. The head 10 has a reduced portion 12 projecting into the housing and in screw threaded engagement therewith. In this instance a coaxially disposed discharge duct 13 communicates with a central discharge chamber 14 in the head, the inner end of the head being reduced to form an annular chamber 15 that communicates with the central chamber 14 through appropriate ports 16. The discharge duct 13 is controlled by a normally closed outwardly opening poppet valve 17 which is actuated and controlled by means hereinafter described.

An annular chamber 18 formed in the upper closed end of the housing 11 constitutes a reservoir for liquid fuel. A duct 19, formed in the wall of the housing 11 and leading downward from the chamber 18, is controlled by an appropriate check valve, such as a ball 20, which is yieldably urged upward into duct-closing position by a spring 21. The ball 20 and spring 21 are housed within an enlarged duct 22, aligned with the duct 19, and communicating with the annular channel 15 hereinabove mentioned. The lower end of the spring 21 is seated upon and supported by a washer 23 seated on the base of the channel 15, the washer having a tab 24 projecting beneath the spring 21 for that purpose.

The chamber 18 is continuously supplied with liquid fuel under pressure from an appropriate pump-fed supply line (not shown) through an appropriate nipple 25 and duct 26 leading upward to the chamber 18, and a nipple 27 arranged near the upper end of the chamber and connected with an appropriate pressure discharge line (not shown) permits a continuous escape of excess or unused liquid fuel from the chamber.

The chamber 18 is closed by an end head 28 hollowed out to receive the upper end of the housing 11 and in screw threaded engagement therewith. A metal disc 29 and sealing washer 30 interposed between the head 28 and the upper end of the housing provide an effective seal for the chamber 18.

It will, of course, be understood that any air or other gases contained in the fuel supplied through the nipple 25 will rise up through the duct 26 and chamber 18 and accumulate within the upper part of the latter, so that the chamber 18 forms an air trap that effectively prevents any air or gas from finding its way downward into the chambers 15 and 14 at the lower end of the housing.

A pump arranged within the housing 11 cooperates with the valve 17 to effect intermittent discharge of measured quantities of liquid fuel through the duct 13.

The pump shown comprises a deformable liquid container 31 within the housing chamber 32. In this instance the container 31 is in the form of a flexible bellows or corrugated flexible tube of metal of high tensile strength, capable of withstanding very high hydraulic pressures and at the same time capable of repeated longitudinal expansion and contraction to repeatedly vary the volumetric capacity thereof. The bellows 31 is supported at its lower end by a heavy ring 33 securely held in place against an internal shoulder 34 of the housing 11 by the nozzle head 10. An upstanding flange 35 on the ring 33 is closely fitted into one end of the bellows and welded or otherwise securely and tightly fixed thereto.

The other end of the bellows is closed by a plug 36 closely fitted therein and welded or otherwise tightly fixed thereto. The plug 36 is preferably cupped or otherwise fashioned to receive the head 37 of a driving plunger 38 guided for lengthwise reciprocation in an appropriate axial bore in the upper closed end of the housing 11.

The plunger 38 is actuated by appropriate mechanism, such for instance as will now be described, which is adjustable to vary the length of stroke thereof. The mechanism shown comprises a plunger 39 coaxially disposed with respect to plunger 38 and guided for reciprocation in a bore 40 in the upper end head 28. The length of stroke of plunger 39 is fixed. The lower end of the plunger 39 coacts with a wedge block 41 to impart a variable stroke to plunger 38. The block 41 in this instance extends lengthwise of and within a transverse channel 43 in the head 28. The block 41 also has a dovetail spline connection 44 with a cylindrical carrier block 45 guided for vertical reciprocation in the bore 40. The carrier block 45 is fixed to the reduced threaded shank 46 of the plunger 38.

The arrangement is such that during each down stroke of the plunger 39 it advances into contact with the wedge block 41 and thereafter causes the blocks 41 and 45 and plunger 38 to move downwardly with it through the remainder of its stroke. By longitudinal adjustment of the wedge block 41 transversely of the plunger 39, the plunger may be caused to engage the same at an earlier or later point in its stroke and thereby cause the plunger 38 to move through a greater or less distance during the remainder of its stroke.

The discharge control valve 17 is rendered responsive to pressures in the chamber of bellows 31 by mechanism shown as comprising a plunger 47 which extends lengthwise of and within the chamber of bellows 31 and which is guided for

lengthwise reciprocation within a bushing 48 fixed centrally of and within the ring 33. The stem 49 of the valve 17 extends loosely through the discharge duct 13 and is adjustably fixed to the lower end of the plunger 47 so as to move therewith. The valve stem is shown screwed into the end of the plunger and locked in adjusted position by a lock nut 50. The valve 17 is normally held in closed position by a compression spring 51 seated at one end upon the bushing 48 and engaged at its other end in a groove 52 formed in the upper end of the plunger 47.

The chamber of bellows 31 communicates at all times with the chamber 14 in the nozzle head 10 preferably through longitudinal grooves 53 formed in that part of the plunger 47 which extends through the bushing 48.

Figure 1 illustrates the relative positions assumed by the parts immediately after completion of an injection or pressure stroke, the plunger 39 having reached the end of its down stroke, and the discharge valve 17 having been instantly closed by the compression spring 51 as a result of a drop in pressure in the pump chamber 31. The bellows 31 is inherently biased to expand so that thereafter, as the plunger 39 retracts, the chamber of bellows 31 expands, forcing the plunger 38 upwardly until arrested by engagement of the head 37 thereof against the upper end wall 54 of the housing chamber 32. It will, of course, be understood that as the bellows 31 expands, it is maintained flooded with liquid fuel supplied under light pressure from the chamber 18 through the ducts 19 and 22, channel 15, ports 16, chamber 14 and grooves 53 in the plunger 47.

During each down stroke of the plunger 39 it ultimately engages the wedge block 41 suddenly forcing it and the plunger 38 downwardly, compressing the liquid filled pump or bellows 31. During this action, the discharge valve 17 remains closed until the pressure in the bellows 31, resulting from the sudden compression thereof, has reached a degree sufficient to overcome the thrust of the spring 51, whereupon this pressure, acting on the plunger 47, effects an instantaneous opening of the valve 17 and the liquid fuel discharges under pressure and at high velocity through the duct 13. The amount of fuel thus discharged is of course dependent upon the extent of compression of the bellows 31, and this is controlled by the length of stroke of the plunger 38 which is regulated by adjustment of the wedge block 41 in the manner above described. At the end of the stroke of the plunger 38, the pressure in the bellows 31 falls off and the spring 51 functions to effect an instantaneous closing of the valve 17 so that the several parts again assume the positions shown in Figure 1.

During normal operation, the upper end of the plunger 47 is spaced from the plug 36 so that it is normally advanced to open the valve 17 solely by the hydraulic pressures within the bellows. But the position of the upper end of this plunger 47 is preferably sufficiently close to the plug 36 as to be mechanically advanced by the advance of the plunger 38 in the event that the pressures in the pump chamber should fail to rise sufficiently to effect the hydraulic advance thereof. In the device shown the arrangement is such that this mechanical advance of the plunger 47 by the plunger 38 can occur only in the event of failure in pump pressures and only during substantially full stroke operation of the variable stroke plunger 38.

It will be noted that as the liquid fuel dis-

charges at high velocity through the orifice 18, it washes the valve 17 and its seat and thereby serves to keep the same clean and free of foreign matter. It will of course be understood that, where the injector is used for cylinder injection, the end of the nozzle is exposed to pressures within the engine cylinder, so that those pressures assist in effecting and insuring prompt closure of the valve 17 after each injection. Objectionable after drip is thus avoided.

It will be further noted that the pump above described is practically leak-proof, since the compression pressures are developed by deformation of the bellows itself rather than by relative movement between closely fitted parts as in ordinary high pressure hydraulic pumps. And since its proper functioning does not depend upon maintenance of close fits between relatively moving parts having mating surfaces subject to wear, this pump is well adapted for use with light liquid fuels, such as gasoline, having little or no lubrication qualities. Moreover, this pump may be produced quite economically because none of the component parts thereof require extremely accurate production methods. Also, by using a pump chamber in the form of an axially compressible bellows of considerable length as compared with the maximum pump stroke, this pump is capable of heavy duty service over long periods of time.

Referring now to the modification illustrated in Figure 4, the injector comprises certain parts similar to some illustrated in Figure 1 and described with respect to said figure. These similar parts are numbered the same as the corresponding parts in Figure 1. However, in order to provide a balanced diaphragm or bellows arrangement, the housing 11 is provided with the fitting 60 having the check valve 62 therein opening toward the bellows 31, the fitting 60 being connected through a suitable pipe 64 to a reservoir, not shown, from which liquid is supplied to the chamber 32. The housing 11 has threaded engagement as at 66 with the end head 68 and the fitting 27 has threaded engagement with the head 68 and the housing 11 and communicates with the chamber 18.

The head 68 has threaded engagement as at 70 with the throttle screw 72 which is adapted to be rotated by any suitable control means, not shown, for moving the throttle screw inwardly or outwardly with respect to the head 68. The throttle screw engages or controls movement of the aligning tab 74, which engages the head 76 of the driving plunger 78 (corresponding to plunger 38), the plunger 78 being independent of the head 80 provided on the plug 36. Head 80 is preferably of hex formation so as to be guidably mounted in the chamber 32 to prevent misalignment of the bellows.

Plunger 82 is reciprocably mounted in the throttle screw 72 and is adapted to be operated by means of a suitable cam. The plunger 78 is urged upwardly by means of the spring 84, one end of which engages the head 76 of the plunger 78, the other end being seated within the recess 86 formed in the upper end 79 of the inner wall of casing 11, which acts as a guide for plunger 78.

It will thus be seen that with this form of device pump operation of the fuel or other fluid from the inside of bellows 31 occurs in the same manner as has already been described with respect to the modification illustrated in Figure 1. The bellows, however, in this instance is balanced, due to the fact that liquid is also supplied

to the chamber 32 through fitting 60 whereby the fluid pressure within the bellows is resisted by the fluid in chamber 32. Reciprocation of the plunger 82 causes reciprocation of the aligning tab 74, plunger 78 and head 80, which in turn pulsates the bellows. The stroke of the bellows is regulated by the throttle screw 72 which moves the aligning tab 74 upwardly or downwardly as viewed in Figure 4 to regulate the amount of movement of the bellows.

In the modification illustrated in Figure 5, a form of injector is illustrated which is adapted for cylinder injection wherein the compression pressure of the cylinder itself is utilized to operate the injector for supplying fuel to the cylinder, to which the injector is connected. The injector comprises the nozzle 82 having threaded engagement as at 84 to one end of the casing or housing 86, a seal 81 being interposed between the nozzle and casing to prevent leakage therebetween.

The opposite end of said housing has a threaded connection as at 88 to the end seal cap 90, said cap being conveniently formed with a suitably shaped head 92 for facilitating assembly. The cap 90 is internally threaded as at 94 for receiving complementary threads of the throttle screw 96, said screw being provided with means such as a lever 98 for rotating the screw to thereby move the screw linearly whereby the stroke of the injector is controlled.

The throttle screw is provided with the bore 100 through which the tubular upper extension 102 of the bellows top seal 104 extends. The tubular extension 102 is provided with the spring pressed check valve 106 opening toward the top seal 104 and the extension 102 is adapted to be connected to a suitable source of fuel supply from which fuel may be supplied under pressure to the extension 102, or the device may operate as its own pump from the source of supply. The top seal 104 is secured between the cap 90 and the shoulder 108 provided on the casing 86 and suitable sealing means may be provided between the top seal and said shoulder.

The top seal is provided with spaced slots 110 through which upstanding fingers 112 of the aligning sleeve 114 extends, said fingers being adapted to abut against the throttle screw 96 for movement thereby. The top seal 104 is provided with the spaced concentric outer and inner rims 116 and 118 to which the upper ends of the bellows 120 and 122 are respectively connected in a leakproof manner, the lower ends of said bellows being similarly secured to the concentric outer and inner spaced rims 124 and 126 respectively of the intermediate seal 128. The seal 128 is provided with the oppositely extending rim 130 to which the upper end of the bellows 132 is connected in a leakproof manner, the lower end of said bellows being similarly connected to the upwardly extending rim 134 of the lower seal 136. The seal 136 is fixedly secured between the nozzle 82 and the casing 86.

The nozzle 82 is provided with the bore 138 terminating in the valve seat 140 on which the injection valve 142 is adapted to seat, the valve and seat being so constructed and arranged that the fuel passing through the bore past the valve will be sprayed. The valve 142 is provided with the stem 144 having a spring seat 146 thereon, a spring 148 being disposed between said seat and the nozzle for normally urging the valve 142 to closed position, the stem being cut out as at 150 for permitting passage of fuel past the

stem. In cutting out the stem 144, it is preferable that the portion 152 of the stem is circular in section while the portions 154 of the cut-out are so arranged that they form lands or guiding means for the valve 142 to insure that said valve always seats properly.

The nozzle 82 is provided with the communicating bores 156 and 158 communicating with the valve seat 160 provided on the casing 86, the valve seat 160 communicating with the bore 162 extending upwardly and communicating with the chamber 164 formed between the casing 86 and the bellows 120. Valve 166 is provided with the valve stem 168 extending upwardly into the chamber 164 to be engaged by the seal 128, said stem being provided with the spring seat 170 on which the upper end of the spring 172 is seated, the lower end of the spring 172 being seated on the shoulder 174 provided in the casing 86 within the bore 162.

The top seal 104 is provided with the depending lower tubular extension 176 extending downwardly to a point adjacent the valve stem 144 whereby when fuel or other fluid is supplied, a cooling action will take place as the relatively cool, newly supplied fuel is introduced at a low point in the nozzle, that is, at the point subjected to the highest temperature.

In operation of this form of the device, assuming that the nozzle is applied to the cylinder of an internal combustion engine, and assuming that valve 142 is closed and the pressure within the bellows 132 and 122 is equal to supply pressure, the pressure within the chamber 164 is the same pressure as that in the engine cylinder, inasmuch as the valve 166 is open. The piston of the cylinder on its compression stroke will then cause a rise in pressure in the chamber 164 causing upward movement of the seal 128, compressing the bellows 120 and 122, which in turn elongates the bellows 132 supplying fuel to the valve 142 under pressure. When the pressure reaches a predetermined amount, valve 142 will be caused to open against the spring 148 permitting injection of the fuel into the cylinder.

Upward movement of the seal 128 will permit the spring 172 and compression pressure to urge the valve 166 towards closed position, and the spring 148 and compression pressure will urge valve 142 toward closed position, so that both valves 142 and 166 are closed during the firing of the fuel in the cylinder. Upward movement of the seal 128 is controlled by the position of the throttle screw 96, that is, the seal 128 will be caused to move upwardly by the engine compression until the fingers 112 of sleeve 114 engage the screw 96.

On the exhaust stroke the products of combustion will be removed from the cylinder with a consequent decrease in pressure. At a predetermined position of the piston, the pressure within the cylinder will be less than the pressure in the chamber 164 at which point the valve 166 will open with a consequent reduction in pressure in the chamber 164. This occurs at the time the seal 128 moves downwardly toward a position where the bellows are restored to their normal position and the valve 166 is open. In this position the injector is in position to repeat the cycle of operation.

In the construction illustrated in Figure 6, the injector comprises nozzle 178 connected as through threads 180 to the casing or housing 182. The casing is connected as through the threads 184 to the end head 186. The end head is pro-

vided with the threads 188 for reception of complementary threads of the throttle screw 190, said throttle screw 190 being provided with operating means such as the lever 192 whereby movement of the lever to rotate the screw 190 causes reciprocation of the screw. The screw is adapted to abut and control the movement of the inner bellows top seal 194 through the projection 196 provided on the seal 194.

The seal 194 is provided with the downwardly extending tubular member 198 extending toward the nozzle 178 and terminating adjacent the valve stem 200. The valve stem 200 is provided with the spring seat 202 forming the upper seat for one end of the spring 204, the lower end of the spring engaging the seat 206 provided in the nozzle. The valve stem is provided with the cut-out portion 208 terminating in the rounded portion 210 disposed adjacent the valve 212, the valve seating on the nozzle seat 214.

The bore 216 in projection 196 communicates with bore 218 to which the inlet fitting 220 is connected. The fitting 220 is provided with the spring loaded valve 222 adapted to seat toward the source of supply. The fitting extends through a suitable enlarged opening 224 in the head 186 and is movable with respect thereto. Thus fuel supplied through the fitting 220 and bores 218 and 216 is introduced to the injector at the hottest point thereof.

The upper end of the inner bellows 226 is secured to the seal 194 in a leakproof manner and a fixed outer seal 228 is secured between the head 186 and the upper end of the casing 182, and the upper end of the outer bellows 230 is secured to the seal 228 in a leakproof manner. The lower ends of the bellows 226 and 230 are respectively secured to the concentric upwardly extending flanges 232 and 234 of the intermediate movable seal 236 in a leakproof manner. The seal 236 is urged downwardly by means of the spring 238, one end of the spring being seated on the seat 240 of the head 186 and the lower end of the spring being seated on the seal 236 between the bellows 226 and 230.

The seal 236 is provided with the oppositely extending flange 242 to which the upper end of the bellows 244 is secured in a leakproof manner, the lower end of said bellows being similarly secured to the bottom seal 246, secured to the casing by means of the lock nut 248.

The nozzle 178 is provided with the bore 250 communicating with the valve bore 252 provided in the casing 182, a spring 254 being interposed between the seal 255, disposed between the casing and the nozzle, and the valve 258 normally urging the valve to seated position in the seat 260. The valve 258 is provided with the upwardly extending stem 262 suitably guided and of a proper configuration to permit passage of fluid past the stem, the stem being adapted to be engaged by the seal 236 whereby movement downwardly by the seal opens the valve 258 and movement upwardly of the seal permits the spring 254 to move the valve towards closed position.

The seal 194 is provided with the outlet fitting 264 connected back to the source of supply, said fitting passing through the enlarged opening 266 provided in the end head, permitting relative movement between the fitting and the head. The fitting communicates with the bore 268, having the valve seat 270 adapted to be closed by the valve 272, the valve being urged towards closed position by means of the spring 274. The valve is provided with the valve stem 276 suitably guided

as at 278 and said stem may likewise be suitably cut away for permitting passage of fluid there-around, the stem being adapted to be engaged by the seal 236 to move the valve 272 to open position. Adjacent the highest point of the bellows 226 an opening 280 is provided whereby should any air be trapped adjacent the top of the bellows, it will be exhausted by the valve 270.

In the operation of this form of the device, assuming that fuel has been supplied from the source of supply through fitting 220 and supply pressure is in the bellows 226 and 244, and assuming that the nozzle is applied for cylinder injection on the compression stroke, the valve 212 will be closed. Compression pressure will be supplied through bore 250, past valve 258 into chamber 282 formed between the bellows 230 and the casing 186. The pressure acting upon the movable seal 236 will cause upward movement thereof, permitting the valve 258 to move towards closed position.

Upward movement of the seal 236 will elongate the bellows 244 and will cause compression of bellows 226, causing fuel to be supplied under pressure to the valve 212 in the nozzle until a predetermined pressure causes opening of said valve 212 with the consequent injection of the fuel. The seal 236 moves upwardly until it engages the stem 276 and continued upward movement of the seal causes the valve 270 to open, thereby relieving the fuel pressure in bellows 244 and causing any air or vapor trapped between the bellows 226 and the seal 194 to be exhausted through fitting 264.

The amount of travel of the seal 236 necessary to open the valve 272 is controlled by the position of the throttle screw. After the predetermined amount of fuel has passed the valve 212, it will close. Valve 258 will remain closed, that is, the seal 236 will not have opened the valve during the power stroke and a portion of the exhaust stroke, at which time there will be a pressure drop in the cylinder and downward movement of the seal 236 will take place by action of the spring 238 and bellows, causing the seal to engage the valve stem 262 to move the valve 258 to open position. When open the pressure in the cylinder and in the chamber will equalize and the device will be in a position to repeat the cycle.

The injector illustrated in Figure 7 is also adapted to utilize the compression pressure of the cylinder to which fuel is to be supplied by the injector for the operation of the injector. The injector comprises a nozzle 284 secured as by threads 286 to the housing or casing 288, the upper end of the casing being closed by means of the end head 290. The head 290 is provided with the inlet fitting 292 adapted to be connected to a suitable source of fuel supply, not shown, said fitting being provided with the spring pressed valve 294 seating toward the source of supply.

The end head is provided with the concentric flanges 296 and 298 to which the upper ends of the outer and inner bellows 300 and 302 are secured in a leakproof manner, the lower ends of said bellows being similarly secured to the outer and inner concentric flanges 306 and 308 of the intermediate movable seal 310. The seal 310 is provided with the oppositely extending flange 312 to which the upper end of the bellows 314 is secured in a leakproof manner, the lower end of said bellows being similarly connected to the lower stationary seal 316 secured between the casing 288 and nozzle 284.

The head 290 is provided with the vents 318

for the space between the bellows 300 and 302 and is also provided with the exhaust valve opening 320 which in turn is connected to the source of supply through a fitting, not shown. The opening 320 is adapted to be closed by means of the valve 322 urged toward closed position by means of the spring 324, said valve being controlled by means of the electro-magnet 326 operated through suitable conductors 328 by suitable throttle control means, not shown, such as by a rotary controlled switch similar to a distributor, the switch being rotated by or in accordance with the operation of the engine, but the length of contact being controlled manually.

The head 290 is also provided with the downwardly extending tube 330 extending to a point adjacent the hottest part of the injector, the tube being in communication with the inlet fitting 292. The nozzle is provided with a spring seat 332 for one end of the spring 334, the other end of the spring being seated on the spring seat 336 provided on the valve stem 338, which is similar to the valve stem 144, and provided with the valve 340 adapted to seat on the nozzle seat 342.

The nozzle is also provided with the bore 344 communicating with the valve bore 346 which in turn communicates with valve stem bore 348, communicating with the chamber 350 formed between the casing 288 and the bellows 300. The valve 352 is adapted to close the seat 354 of bore 348, the valve being urged toward closed position by means of the spring 356 disposed between the seat 358, provided in the casing 288, and the seat 360 provided on the flattened valve stem 362. The valve stem 362 extends upwardly and is adapted to be contacted by the movable seal 310, downward movement of the seal 310 causing valve 352 to be opened.

On the compression stroke, valve 340 is closed and valve 352 is open and compression pressure will then be introduced to the chamber 350, causing upward movement of the seal 310 to elongate the bellows 314 and compress the bellows 302, causing a predetermined amount of fuel to be supplied under pressure to the valve 340 causing the valve to open and inject a predetermined amount of fuel into the cylinder. This predetermined amount of fuel is determined by operation of the electro-magnet 326 to open the valve 322, reducing the pressure at the valve 340 to permit the spring 334 (and cylinder pressure) to close said valve. Predetermined upward movement of the seal 310 as limited by the shoulder 327, will permit the spring 356 to close the valve 352 for the power stroke and a predetermined portion of the exhaust stroke of the engine. The compression pressure in the cylinder is reduced on the exhaust stroke to a predetermined amount, at which time valve 352 will be permitted to open, equalizing the pressures in the chamber 350 and the cylinder, causing downward movement of the seal 310 by the return of the bellows to normal position, urging the valve 352 to fully open position, at which time the injector is in position for repeating the cycle.

In the construction shown in Figure 8, an injector is illustrated which is not dependent upon compression pressure for its operation so that it may be timed to inject fuel on the intake stroke of an engine or on the compression stroke thereof. This injector consists essentially of the nozzle 364 secured as by means of the threads 366 to the housing or casing 368, the upper portion of the casing being closed by means of the end head 370. The end head is provided with the inlet fit-

ting 372 adapted to be connected to a suitable source of supply and being provided with a spring pressed valve 374 closing toward the source of supply.

5 The head 370 is provided with the electro-magnet 376 connected through suitable conductors 378 to a throttle control, such as described with respect to Figure 7, said electro-magnet being adapted to open the spring pressed outlet valve 380 controlling the outlet opening 382 which is connected back to the source of supply. The spring of said valve urges the valve to closed position.

15 The head 370 is provided with the depending spaced concentric flanges 384 and 386 to which are secured in a leak-proof manner the upper ends of the outer and inner bellows 388 and 390. The space between the bellows is vented as through openings 392. The lower ends of the 20 bellows are similarly connected to the outer and inner concentric flanges 394 and 396, respectively, of the movable seal 398, said seal being urged upwardly by means of the spring 400, one end of the spring seating on the seal 398 and the other 25 end of the spring seating on seat 402 of the casing.

The casing is provided with the electro-magnet 404 connected through suitable conductors 406 to operating means, as for example, a rotary switch operated by the engine and so constructed and arranged that the electro-magnet is energized any time after injection has ceased, for example, on the suction stroke up until the time that injection is initiated, at which time the electro-magnet 404 is de-energized.

35 The seal 398 is provided with the flange 408 to which the upper end of the bellows 410 is secured in a leakproof manner, the lower end of the bellows being similarly secured to the fixed seal 412 secured between the casing 368 and the 40 nozzle 364. The head 370 is also provided with the downwardly extending tubular member 414 in communication with the fitting 372 and extending to a point adjacent the nozzle whereby cool fuel is supplied to the hottest part of the 45 injector.

The nozzle is provided with the valve seat 416 adapted to be closed by the valve 418, the valve being provided with the stem 420 similar to the stem 144 (Figure 5) said stem being provided with 50 the spring seat 422, for one end of the spring 424, the lower end of the spring being seated on the seat 426 of the nozzle.

In operation of this form of the device the electromagnet 404 is energized at some time after 55 injection has ceased, for example, on the compression stroke, causing downward movement of the seal 398, elongating bellows 390 and compressing bellows 410 and fuel is supplied through the fitting 372 to the inside of bellows 410, 390, and 60 spring 400 is compressed. At a suitable time prior to the time the piston of the cylinder has completed its compression stroke, the electro-magnet 404 is de-energized, permitting spring 400 to move the seal 408 upwardly, causing fuel under pressure 65 to be supplied to the valve 418 and injected into the cylinder. The amount of fuel is regulated by energizing electro-magnet 376 which will open valve 380 to terminate injection. The pumping stroke of the bellows, as determined by 70 the movement of the seal 398 is always the same, regardless of the speed of the motor as it moves from the lowermost position when the electro-magnet 404 is energized to its uppermost position when magnet 404 is de-energized, against the stop 405 formed in the body of the

upper electro-magnet but the amount of fuel that is injected is controlled by the valve 380. The pumping stroke, then, of this device is governed not by the speed of the engine, but by the capacity of the spring 400.

In the construction illustrated in Figures 9 to 12 inclusive, there is shown an injector for use in a cylinder for supplying fuel to that cylinder wherein the operation of said injector is controlled from an adjacent cylinder, it being understood, of course, that the fuel from the injector may also be supplied to a manifold.

The injector comprises the casing 428 corresponding to the casing 11 (Figure 1), it being understood that there is provided a nozzle corresponding to the head 10, a nozzle valve corresponding to the nozzle valve 17, the valve being controlled by the linear movement of the plunger 430 (corresponding to plunger 47) controlled by the pumping action of the bellows 432 (corresponding to bellows 31). The casing 428 is provided with the bore 434 (corresponding to bore 19) and a valve corresponding to the valve 29 and operating similarly thereto, of course, is provided.

Fuel is supplied from a suitable source of supply through fitting 436 (corresponding to fitting 25), communicating with bore 438 (corresponding to bore 26) which in turn communicates with chamber 440 (corresponding to chamber 18), circulation of fuel being effected through the chamber and out the fitting 442 (corresponding to fitting 27). The nozzle valve is urged towards closed position by means of a spring 444 (corresponding to spring 51) and the top of the bellows is closed by means of the plug 446 (corresponding to plug 36) said plug being provided with a head 448 having a hex portion for guiding the reciprocatory movement of the head.

The extent of movement of the head is controlled by means of the plunger 450 mounted for reciprocation in the end head 452 and being provided with piston ring 454 to prevent the escape of fluid around the plunger 450. The head 452 is threaded as at 456 for the reception of complementary threads of the throttle screw 458 provided with a suitable throttle lever 460 controlled as desired. Rotation of the throttle screw 458 will cause linear movement of the plunger 450 to control movement of the bellows 432. In order to effect actuation of the bellows a fitting 462 is provided communicating with the chamber 464 formed between the bellows and the casing. The fitting 462 is connected through the pipe 466 to the compression check valve 468 (Figure 12) through fitting 470.

In Figure 10 there is illustrated the six cylinders 472, 474, 476, 478, 480 and 482 of a six cylinder internal combustion engine, the numbers being given in rotation from 1 to 6 and the piston position of each of the cylinders being shown, it being assumed that the piston of number 1 cylinder (472) is starting to compress as the crank position of the piston therein is in the position as illustrated in Figure 11, and the injector is starting to inject.

The pistons in Figure 10 are in the relative positions as shown by the crank positions of Figure 11. The firing order is 1, 5, 3, 6, 2, 4. Thus while only one injector is illustrated, it will, of course, be understood that cylinder 472 is fired by cylinder 474, cylinder 474 by cylinder 476, cylinder 476 by cylinder 472, cylinder 478 by cylinder 482, cylinder 480 by cylinder 478, and cylinder 482 by cylinder 480. Thus each cylinder

will have an injector and a compression check valve running to its respective injector. It will be sufficient to describe only one compression check valve (Figure 12) connected to its respective injector (Figure 9).

The compression check valve 468 (Figure 12) comprises the valve seat compression base 484 suitably secured to the respective cylinder (shown as 474 in Figures 10 and 11) and is provided with the valve seat 486 for the valve 488, said valve closing in a direction away from the piston. The valve is provided with the valve stem 490 connected to the diaphragm 492 suitably secured as at 494 between flange 496 of the base 484 and the corresponding flange 498 of the cap 500.

The cap 500 is provided with the adjusting screw 502 having a lock nut 504 thereon, said screw extending inwardly of the cap for controlling the compression of spring 506 seated at one end on the screw and at the other end on the diaphragm 492. The cap is vented to the atmosphere as at 508 and spring 506 normally urges the valve 488 to open position.

While Figures 9 to 12 show a form of device wherein compression pressure is transmitted to the chamber 464, it is, of course, understood that the compression pressure may be transmitted to liquid contained in the chamber 464. This is accomplished by providing fitting 509 (similar to fitting 60) having a spring pressed check valve 511 opening toward chamber 464 and connected through pipe 513 (similar to pipe 64) to a source of liquid supply. Cylinder 472 is just starting to compress and cylinder 474 is towards the end of its compression stroke. Compression pressure is then transmitted past valve 488 to chamber 464 compressing the bellows to cause injection as described with respect to Figure 1. After a predetermined pressure has been built up by cylinder 474 as it approaches the end of its compression stroke, pressure on the diaphragm 492 will overcome the spring 506 to close the valve 488 to cause cessation of operation of the injector of cylinder 472. Valve 488 will remain closed in cylinder 472 through the entire power stroke and thereafter the pressure drop in cylinder 474 will permit the spring 506 to open valve 488 as pressure is relieved from valve 488 in the cylinder 474. The same operation, of course, occurs in each of the pairs of cylinders operated in accordance with the above.

In the construction illustrated in Figure 13, the injector 510 consists essentially of the casing 512 secured as at 514 to the nozzle head 516, suitable sealing means 518 being provided therebetween. The upper head 520 of the casing is suitably threaded as at 522 for the reception of the throttle screw 524 provided with the throttle means 526. Rotation of the throttle means 526 causes linear movement of the screw 524, the end of which projects within the casing 512 limiting upward movement of the upper bellows end seal 528 which is preferably of hex shape whereby it is guided in its reciprocatory movement within the cylinder, the cylinder above the seal 528 being vented as at 530.

The seal 528 is fixedly secured in a leakproof manner to the upper end of the inner and outer bellows 532, 534. A lower seal 536 is secured between the nozzle 516 and the shoulder 538 provided in the casing, suitable sealing means 540 being interposed between the seal 536 and nozzle. The lower ends of bellows 532 and 534 are fixedly connected in a leakproof manner to the concen-

tric flanges 542 and 544 provided on the lower seal 538, whereby a fuel chamber 546 and a vacuum chamber 548 is formed.

Chamber 546 communicates through bore 550 with the fitting 552 provided with the check valve 554 opening towards chamber 546, the fitting 552 being connected to a suitable source of fuel supply. Chamber 548 communicates through bore 556 with the pipe 558 which in turn is connected through the valve 560 to the engine cylinder 562, said cylinder being the cylinder supplied by fuel from the injector 510 and the cylinder operating said injector, it being understood, of course, that the injector may be supplied with fuel directly from the injector or through a manifold. The valve 560 opens towards the cylinder 562, and the nozzle 516 of the injector is provided with the valve seat 564 adapted to seat the valve 566, which is of similar configuration to the valve in Figure 5, the valve being provided with the cut away stem 568 and having the spring seat 570 thereon on which the upper end of the spring 572 is seated, the lower end of said spring being seated on the seat 574.

In operation of this form of the device, suction in cylinder 562 will be transmitted to the chamber 548 between the bellows causing the seal 528 to move downwardly compressing said bellows, causing fuel within the chamber 546 to open the valve 566 for supplying the measured fuel to the cylinder 562. After completion of the injection, valve 560 will close, due to the upward movement of the piston cylinder 562 permitting the bellows to return the seal 528 upwardly permitting spring 572 to close valve 566 and drawing fuel through fitting 552 into chamber 546.

Referring now to Figure 14, there is shown injectors 576, 578, 580, 582, 584 and 586 similar to the injector described in Figure 1, said injectors being for cylinders 1 to 6 respectively of a six cylinder engine. Each injector is provided with a fitting 588 (corresponding to fitting 27, Figure 1) which in turn is connected back to the source of fuel supply, not shown. The inlet fitting (25 in Figure 1) is connected to branch pipes 590 of the manifold 592 and each unit is operated by its respective cam 594 rotated by a suitable cam shaft.

The inlet side of the manifold 592 is connected through the pipe 593 to the outlet side of a suitable pressure type supply pump 598, the inlet side of said pump being connected through pipe 600 to the suitable source of fuel supply. The pump 598 is provided with the by-pass 602 from pump pressure to suction and in said by-pass there is disposed a valve 604. The valve 604 is a normally opened valve whereby when the engine is in operation it normally operates at low speed. The valve may consist of the housing 606 having an inlet 608 connected to the pump pressure (outlet), the outlet 610 of the housing 606 being connected to the pump suction (inlet).

Valve 612 is urged toward fully open position by means of the spring 614, said valve in closed position being adapted to seat on seat 616. The valve is provided with the valve stem 618 controlled by means of the pivoted lever 620. Operation of the lever 620 to close the valve 612 will cause the pump 598 to supply an increased amount of fuel to the injectors to thereby increase the amount of fuel supplied to the respective cylinders.

Comparison of Load-Speed control of injectors of known type and those illustrated herein

In order to obtain the degree of control over the ratio of air and fuel (needed for optimum economy and satisfactory performance) that is introduced into an engine cylinder, it is essential that the quantity of fuel per injection be maintained at a fixed ratio with respect to the quantity of air inducted per suction stroke of the engine cylinder.

In a naturally aspirated (not supercharged) internal combustion engine the quantity of air inducted per suction stroke of the engine decreases with increases in engine speed for each and every air throttle position according to the volumetric-efficiency curve (breathing rate) of the engine.

Thus it is evident that if a constant ratio of air and fuel is to be maintained at all times and under all conditions of speeds and loads (Load-Speed Control), the "speed-delivery" characteristic of the injection system should conform to the same general form as the volumetric-efficiency curve of the engine.

20 In an engine operating on the Otto cycle (such as a gasoline spark-ignition engine) it is necessary to control one air-charge inducted by a throttle control over the air as well as the fuel introduced to the engine. Thus there is a family

30 of volumetric-efficiency curves (one curve for each throttle position). In the Diesel engine, as no air throttle is provided, there is only one volumetric-efficiency curve for the air charge inducted (full throttle).

35 All commercial forms of fuel injection pumps now in use utilize a plunger-barrel combination, as a pumping means. The type of injection pump in most extensive use at the present time, employs a port controlled by-pass, with an undercut section of the plunger as the slide valve means for controlling the porting of this by-pass port in order to control the quantity of fuel delivered by the pump.

The following formula expresses the leakage rate of the above type of plunger-barrel pumps.

$$\text{Leakage rate} \propto \frac{c l^3 d s P}{\mu L}$$

- 50 1. c is a constant.
2. l is the mean clearance between the barrel or casing and the plunger.
3. d is the pump plunger diameter.
4. s is the plunger velocity.
5. P is the pressure differential between the lapped portion between the plunger and the barrel.

60 6. μ is the viscosity of the liquid being pumped.
7. L is the length of the lapped fit.

Due to the leakage condition it is necessary in this piston type of pump to provide a cam profile with a rate of lift sufficient to overcome this leakage at slow speeds, especially cranking speeds as are encountered when cold-starting the engine. As a result, the speed-delivery characteristics of this type of pump tend to fall off at slow speeds (when the time for leakage is the greatest) and also at high speeds (when the pressure causing leakage is the greatest).

70 As a result of the above conditions the tendency at the higher throttle rack settings is to result in speed-delivery characteristics, which fall off much more rapidly with increasing engine speed than the Volumetric Efficiency of the engine does, and results in the failure to maintain the air to fuel ratio.

As the throttle rack position is decreased (smaller amounts per injection), the "speed-delivery" characteristics continue to be altered until at the lower range of the throttle settings the curve has an exactly opposite slope. This condition is equally as undesirable as the former.

Thus it may be seen that as the quantity per injection at the higher throttle conditions falls off too rapidly due to leakage, there will be a speed at which delivery will fall below the quantities necessary, and result in a definite limit to engine speeds that can be obtained. This condition is especially bad when the high pressure pump and nozzle are separated by a delivery tube (due to adverse pressure wave characteristics).

In the modifications shown herein the effect of leakage is eliminated by the use of a hermetically sealed pumping element, and a unitary construction is employed in order to overcome the disadvantage of a pump-delivery-tube-nozzle combination. The absence of leakage makes possible the use without adverse effects of whatever cam shape is necessary in order that the "speed-delivery" characteristics of the injector will conform exactly to the Volumetric-Efficiency curve of the engine. Thus in the modifications herein, it is possible to obtain complete and automatic Load-Speed Control.

The injectors shown herein may readily be operated as pusher or sump pumps located at the source of supply and supplying fuel to injectors or a carburetor, also they may be used to inject liquid, as water, into the cylinders (or manifold) for anti-detonating purposes.

It is to be understood that I do not wish to be limited by the exact embodiments of the device shown, which are merely by way of illustration and not limitation as various and other forms of the device will, of course, be apparent to those skilled in the art without departing from the spirit of the invention or the scope of the claims.

I claim:

1. In an injector, the combination of a housing having a chamber connected to an inlet and an outlet, a second chamber connected to said first chamber, a valve controlling flow from said first chamber to said second chamber, a movable member in said second chamber, a flexible bellows connected at one end to said movable member and connected at the other end to said housing so that it communicates with said second chamber, a nozzle having a nozzle valve controlling egress from said second chamber, a connection adapted to be associated with a source of pressure supply for pulsating said bellows to control the nozzle valve, a closure cap for said housing, and a member having a seal ring extending into said housing to control movement of said bellows.

2. In an injector, the combination of a housing having a chamber connected to an inlet and an outlet, a second chamber connected to said first chamber, a valve controlling flow from said first chamber to said second chamber, a movable member in said second chamber, a flexible bellows connected at one end to said movable member and connected at the other end to said housing so that it communicates with said second chamber, a nozzle having a nozzle valve controlling egress from said second chamber, a connection adapted to be associated with a source of pressure supply for pulsating said bellows to control the nozzle valve, said connection including a member having a chamber communicating with said last cylinder, flexible means in said

chamber and a valve for closing communication with said cylinder, pressure on said flexible means controlling said valve.

3. In a fuel injector, the combination of a housing having a housing chamber therein, one end of said housing having a wall forming a closure for one end of said chamber, said wall having a passage therethrough, a driving plunger reciprocably mounted in said passage and having a plunger head disposed in said chamber, said housing having a trap chamber at said last named end of said housing, an end head for closing said end of said housing and said trap chamber, a closure head fixed to the other end of said housing and forming a closure therefor, a fixed ring secured between said housing and closure head and having a substantially cylindrical flange extending into said housing chamber, a flexible bellows disposed in said housing chamber and having one end secured to said flange and the other end secured to said plunger head, means extending into said end head movable and adjustable to reciprocate said plunger selected amounts, a fuel inlet to said trap chamber, a fuel outlet from said trap chamber above the fuel inlet thereto, said closure head having a discharge duct terminating in an outer valve seat, said closure head having a discharge chamber communicating with said discharge duct and the inside of said bellows, a plunger slidably mounted in said fixed ring and having one end disposed in said discharge chamber and having the other end extending into said bellows, a valve seating on said seat and secured to the end of said last named plunger in said discharge chamber for controlling discharge through said duct, the end of said last named plunger within said bellows being spaced from

4. In a fuel injector, the combination of a housing having a housing chamber therein, one end of said housing having a wall forming a closure for one end of said chamber, said wall having a passage therethrough, a driving plunger reciprocably mounted in said passage and having a plunger head disposed in said chamber, said housing having a trap chamber at said last named end of said housing, an end head for closing said end of said housing and said trap chamber, a closure head fixed to the other end of said housing and forming a closure therefor, a fixed ring secured between said housing and closure head and having a substantially cylindrical flange extending into said housing chamber, a flexible bellows disposed in said housing chamber and having one end secured to said flange and the other end secured to said plunger head, means extending into said end head and adjustable to control reciprocation of said plunger, a fuel inlet to said trap chamber, a fuel outlet from said trap chamber, said closure head having a discharge duct, said closure head having a discharge chamber communicating with said discharge duct and the inside of said bellows, a plunger slidably mounted in said fixed ring and having one end disposed in said discharge chamber and having the other end extending into said bellows, a valve secured to the end of said last named plunger in said discharge chamber for controlling discharge through said duct, the end of said last named plunger within said bellows being spaced from

the plunger head when said valve is closed, resilient means urging said valve toward closed position, said housing having a passage connecting said trap chamber and said discharge chamber, and a valve in said last named passage opening toward said discharge chamber.

5. In a fuel injector, the combination of a housing having a housing chamber therein, one end of said housing having a wall forming a closure for one end of said chamber, said wall having a passage therethrough, a driving plunger reciprocably mounted in said passage and having an end disposed in said chamber, said housing having a trap chamber at said last named end of said housing, an end head for closing said end of said housing and said trap chamber, a closure head fixed to the other end of said housing and forming a closure therefor, a flexible bellows disposed in said housing chamber and having one end secured to said housing and the other end closed, the closed end being disposed within said housing chamber adjacent said plunger, means adjustable to reciprocate said plunger selected amounts, a fuel inlet to said trap chamber, a fuel outlet from said trap chamber, said closure head having a discharge duct, said closure head having a discharge chamber communicating with said discharge duct, a member between said bellows and closure head having a passage communicating with the inside of said bellows and said discharge chamber, a plunger slidably mounted in said last named member having one end disposed in said discharge chamber and having the other end extending into said bellows, a valve secured to the end of said last named plunger in said discharge chamber for controlling discharge through said duct, the end of said last named plunger within said bellows being spaced from the closed end of said bellows when said valve is closed, resilient means urging said valve toward closed position, said housing having a passage connecting said trap chamber and said discharge chamber, and a valve in said last named passage opening toward said discharge chamber.

6. In a fuel injector, the combination of a housing having a housing chamber therein, one end of said housing having a wall forming a closure for one end of said chamber, said wall having a passage therethrough, a driving plunger reciprocably mounted in said passage and having an end disposed in said chamber, an end head for closing said end of said housing, a closure head fixed to the other end of said housing and forming a closure therefor, a flexible bellows disposed in said housing chamber and having one end secured to said housing and the other end closed, the closed end being disposed within said housing chamber adjacent said plunger, means adjustable to reciprocate said plunger selected amounts, a fuel inlet to said housing, a fuel outlet from said housing, said housing having a connection between inlet and outlet, said closure head having a discharge duct, said closure head having a discharge chamber communicating with said discharge duct, a member for closing the other end of said housing chamber and having a passage communicating with the inside of said bellows and said discharge chamber, a plunger slidably mounted in said last named member having one end disposed in said discharge chamber and having the other end extending into said bellows, a valve secured to the end of said last named plunger in said discharge chamber for controlling discharge through said

duct, the end of said last named plunger within said bellows being spaced from the closed end of said bellows when said valve is closed, resilient means urging said valve toward closed position, said housing having a passage connecting said connection between inlet and outlet and said discharge chamber, and a valve in said last named connection opening toward said discharge chamber.

7. In a fuel injector, the combination of a housing having a housing chamber therein, said housing having a closure for one end of said housing and chamber, a closure head fixed to the other end of said housing and forming a closure therefor, a flexible bellows disposed in said housing chamber and having one end secured to said housing and the other end closed, the closed end being disposed within said housing chamber adjacent the closed end of said housing chamber, means for controllably moving the closed end of said bellows toward and away from the fixed end of said bellows, a fuel inlet to said housing and a fuel outlet from said housing, said housing having a connection between inlet and outlet, said closure head having a discharge chamber and a discharge duct from said discharge chamber, a member at the other end of said housing chamber having a passage communicating with the inside of said bellows and said discharge chamber, a plunger slidably mounted in said last named member having one end disposed in said discharge chamber and having the other end extending into said bellows, a valve secured to the end of said last named plunger in said discharge chamber for controlling discharge through said duct, the end of said last named plunger within said bellows being spaced from the closed end of said bellows when said valve is closed, resilient means urging said valve toward closed position, said housing having a passage connecting said connection between inlet and outlet and said discharge chamber, and a valve in said last named connection opening toward said discharge chamber.

8. In a fuel injector, the combination of a housing having a housing chamber therein, one end of said housing having a wall forming a closure for one end of said chamber, said wall having a passage therethrough, a driving plunger reciprocably mounted in said passage and having an end projecting into said housing chamber, said housing having a trap chamber at said last named end of said housing, an end head for closing said end of said housing and said trap chamber, a closure head fixed to the other end of said housing and forming a closure therefor, a fixed ring secured between said housing and closure head and having a substantially cylindrical flange extending into said housing chamber, a flexible bellows disposed in said housing chamber and having one end secured to said flange and the other end closed and disposed adjacent said wall, means extending into said end head movable and adjustable to reciprocate said plunger selected amounts, resilient means urging said plunger toward said last named means and away from the closed end of said bellows, a fuel inlet to said trap chamber, a fuel outlet from said trap chamber above the fuel inlet thereto, said closure head having a discharge duct terminating in an outer valve seat, said closure head having a discharge chamber communicating with said discharge duct and the inside of said bellows, a plunger slidably mounted in said fixed ring and having one end disposed in said discharge chamber and having the other end extending into said bellows, a valve

seating on said seat and secured to the end of said last named plunger in said discharge chamber for controlling discharge through said duct, the end of said last named plunger within said bellows being spaced from the closed end of said bellows and said closed end of said bellows being spaced from the end of said driving plunger in said housing chamber when said valve is closed, resilient means urging said valve toward closed position, said housing having a passage connecting said trap chamber and said discharge chamber, a valve in said last named passage opening toward said discharge chamber, a connection to said housing communicating with said housing chamber externally of said bellows, and a valve in said last named connection opening toward said housing chamber whereby liquid is supplied to said housing chamber externally of said bellows.

9. In a fuel injector, the combination of a housing having a housing chamber therein, one end of said housing having a wall forming a closure for one end of said chamber, said wall having a passage therethrough, a driving plunger reciprocably mounted in said passage and having an end projecting into said housing chamber, said housing having a trap chamber at said last named end of said housing, an end head for closing said end of said housing and said trap chamber, a closure head fixed to the other end of said housing and forming a closure therefor, a fixed ring secured between said housing and closure head and having a substantially cylindrical flange extending into said housing chamber, a flexible bellows disposed in said housing chamber and having one end secured to said flange and the other end closed and disposed adjacent said wall, means extending into said end head and adjustable to control reciprocation of said plunger, a fuel inlet to said trap chamber, a fuel outlet from said trap chamber, said closure head having a discharge duct, said closure head having a discharge chamber communicating with said discharge duct and the inside of said bellows, a plunger slidably mounted in said fixed ring and having one end disposed in said discharge chamber and having the other end extending into said bellows, a valve secured to the end of said last named plunger in said discharge chamber for controlling discharge through said duct, the end of said last named plunger within said bellows being spaced from the closed end of said bellows and said closed end of said bellows being spaced from the end of said driving plunger in said housing chamber when said valve is closed, resilient means urging said valve toward closed position, said housing having a passage connecting said trap chamber and said discharge chamber, a valve in said last named passage opening toward said discharge chamber, a connection to said housing communicating with said housing chamber externally of said bellows, and a valve in said last named connection opening toward said housing chamber whereby liquid is supplied to said housing chamber externally of said bellows.

10. In a fuel injector, the combination of a housing having a housing chamber therein, one end of said housing having a wall forming a closure for one end of said chamber, said wall having a passage therethrough, a driving plunger reciprocably mounted in said passage and having an end projecting into said chamber, said housing having a trap chamber at said last named end of said housing, an end head for closing said end of said housing and said trap chamber, a closure

head fixed to the other end of said housing and forming a closure therefor, a flexible bellows disposed in said housing chamber and having one end secured to said housing and the other end closed and disposed adjacent said wall, means adjustable to reciprocate said plunger selected amounts, resilient means urging said plunger toward said last named means and away from the closed end of said bellows, a fuel inlet to said trap chamber, a fuel outlet from said trap chamber, said closure head having a discharge duct, said closure head having a discharge chamber communicating with said discharge duct, a member between said bellows and closure head having a passage communicating with the inside of said bellows and said discharge chamber, a plunger slidably mounted in said last named member having one end disposed in said discharge chamber and having the other end extending into said bellows, a valve secured to the end of said last named plunger in said discharge chamber for controlling discharge through said duct, the end of said last named plunger within said bellows being spaced from the closed end of said bellows and said closed end of said bellows being spaced from the end of said driving plunger in said housing chamber when said valve is closed, resilient means urging said valve toward closed position, said housing having a passage connecting said trap chamber and said discharge chamber, a valve in said last named passage opening toward said discharge chamber, a connection to said housing communicating with said housing chamber externally of said bellows, and a valve in said last named connection opening toward said housing chamber whereby liquid is supplied to said housing chamber externally of said bellows.

11. In a fuel injector, the combination of a housing having a housing chamber therein, one end of said housing having a wall forming a closure for one end of said chamber, said wall having a passage therethrough, a driving plunger reciprocably mounted in said passage and having an end projecting into said housing chamber, an end head for closing said end of said housing, a closure head fixed to the other end of said housing and forming a closure therefor, a flexible bellows disposed in said housing chamber and having one end secured to said housing and the other end closed and disposed adjacent said wall, means adjustable to reciprocate said plunger selected amounts, resilient means urging said plunger toward said last named means and away from the closed end of said bellows, a fuel inlet to said housing, a fuel outlet from said housing, said housing having a connection between inlet and outlet, said closure head having a discharge duct, said closure head having a discharge chamber communicating with said discharge duct, a member for closing the other end of said housing chamber and having a passage communicating with the inside of said bellows and said discharge chamber, a plunger slidably mounted in said last named member having one end disposed in said discharge chamber and having the other end extending into said bellows, a valve secured to the end of said last named plunger in said discharge chamber for controlling discharge through said duct, the end of said last named plunger within said bellows being spaced from the closed end of said bellows and said closed end of said bellows being spaced from the end of said driving plunger in said housing chamber when said valve is closed, resilient means urging said valve toward closed position, said housing having a passage connect-

ing said connection between inlet and outlet and said discharge chamber, a valve in said last named connection opening toward said discharge chamber, a connection to said housing communicating with said housing chamber externally of said bellows, and a valve in said last named connection opening toward said housing chamber whereby liquid is supplied to said housing chamber externally of said bellows.

12. In a fuel injector, the combination of a housing having a housing chamber therein, said housing having a closure for one end of said housing and chamber, a closure head fixed to the other end of said housing and forming a closure therefor, a flexible bellows disposed in said housing chamber and having one end secured to said housing and the other end closed, the closed end being disposed within said housing chamber adjacent the closed end of said housing chamber, means for controllably moving the closed end of said bellows toward and away from the fixed end of said bellows, a fuel inlet to said housing and a fuel outlet from said housing, said housing having a connection between inlet and outlet, said closure head having a discharge chamber and a discharge duct from said discharge chamber, a member at the other end of said housing chamber having a passage communicating with the inside of said bellows and said discharge chamber, a plunger slidably mounted in said last named member having one end disposed in said discharge chamber and having the other end extending into said bellows, a valve secured to the end of said last named plunger in said discharge chamber for controlling discharge through said duct, the end of said last named plunger within said bellows being spaced from the closed end of said bellows, and the closed end of said bellows being spaced from the closed end of said housing chamber when said valve is closed, resilient means urging said valve toward closed position, said housing having a passage connecting said connection between inlet and outlet and said discharge chamber, a valve in said last named connection opening toward said discharge chamber, a connection to said housing communicating with said housing chamber externally of said bellows, and a valve in said last named connection opening toward said housing chamber whereby liquid is supplied to said housing chamber externally of said bellows.

13. In a fuel injector, the combination of a housing having a housing chamber therein, said housing having a closure for one end of said housing and chamber, a closure head fixed to the other end of said housing and forming a closure therefor, a fuel inlet to said housing and a fuel outlet from said housing, said housing having a connection between inlet and outlet, said closure head having a discharge duct, said injector having a discharge chamber communicating with said duct, a flexible member fixed to said housing and disposed between said housing chamber and said discharge chamber, said housing having a passage connecting said connection between inlet and outlet and said discharge chamber, a valve in said last named connection opening toward said discharge chamber, a valve opening away from said discharge chamber for controlling flow through said duct, a connection to said housing communicating with said housing chamber, a valve in said last named connection opening toward said housing chamber whereby liquid is supplied to said housing chamber, and means movable in said first named closure selectively adjusta-

bly displacing the liquid in said housing chamber to move said flexible member toward and away from the closure head to displace the fuel in said discharge chamber to serially and alternately open the duct controlling valve and simultaneously close the valve between the fuel inlet and the discharge chamber, and thereafter close the duct controlling valve and simultaneously open the valve between the fuel inlet and the discharge chamber.

14. In a fuel injector, the combination of a housing having a housing chamber therein, said housing having a closure for one end of said housing and chamber, a closure head fixed to the other end of said housing and forming a closure therefor, a fuel inlet to said housing and a fuel outlet from said housing, said housing having a connection between inlet and outlet, said closure head having a discharge duct, said injector having a discharge chamber communicating with said duct, a flexible member fixed to said housing and disposed between said housing chamber and said discharge chamber, said housing having a passage connecting said connection between inlet and outlet and said discharge chamber, a valve in said last named connection opening toward said discharge chamber, a valve opening away from said discharge chamber for controlling flow through said duct, a connection to said housing communicating with said housing chamber, a valve in said last named connection opening toward said housing chamber whereby liquid is supplied to said housing chamber, a connection for supplying pulsations to said housing chamber to move said flexible member to displace the fuel in said discharge chamber whereby it is expelled through said duct, and means movable in said first named closure to change the volume in said chamber to thereby affect the flexing of said flexible member.

15. In a fuel injector, the combination of a housing having an end closure at one end of said housing, said housing having a closure for the other end of said housing having a discharge duct therethrough, a flexible member secured in said housing and having one surface defining a housing chamber in said housing, said housing chamber communicating with said duct, a discharge valve in said second named closure resiliently urged toward closed position and opening outwardly of said housing for controlling flow through said duct from said housing chamber, an inlet valve connected to said housing and having an inlet side adapted to be connected to a source of supply and having the outlet side opening toward said housing chamber to admit fuel thereto and to said surface of said flexible member, said valve being resiliently urged toward closed position, an outlet connected to a passage communicating with the inlet side of said inlet valve, means operable on the other surface of said flexible member for reciprocating said flexible member causing reciprocations of said flexible member with respect to said duct, and means movable to regulate the stroke of said last named means.

16. In a fuel injector, the combination of a housing having an end closure at one end of said housing, said housing having a closure for the other end of said housing having a discharge duct therethrough, a flexible member secured in said housing and forming housing chambers in said housing, one of said housing chambers communicating with said duct, a discharge valve in said

second named closure resiliently urged toward closed position and opening outwardly of said housing for controlling flow through said duct from said last named housing chamber, an inlet valve connected to said housing and having an inlet side adapted to be connected to a source of supply and having the outlet side opening toward said last named housing chamber to admit fuel thereto, said valve being resiliently urged toward closed position, an outlet connected to a passage communicating with the inlet side of said inlet valve, a valve connected to said other housing chamber for supplying fluid under pressure thereto, means for reciprocating said flexible member causing reciprocations of said flexible member with respect to said duct, and means movable to regulate the stroke of said last named means.

17. In a fuel injector, the combination of a housing having an end closure at one end of said housing, said housing having a closure for the other end of said housing having a discharge duct therethrough, a flexible member secured in said housing and forming housing chambers in said housing, one of said housing chambers communicating with said duct, a discharge valve in said second named closure resiliently urged toward closed position and opening outwardly of said housing for controlling flow through said duct from said last named housing chamber, an inlet valve connected to said housing and having an inlet side adapted to be connected to a source of supply and having the outlet side opening toward said last named housing chamber to admit fuel thereto, said valve being resiliently urged toward closed position, an outlet connected to a passage communicating with the inlet side of said inlet valve, a valve connected to said other housing chamber for supplying fluid under pressure thereto, means disposed in said last named housing chamber movable toward and away from said flexible member causing reciprocations of said flexible member with respect to said duct, and means movable to regulate the stroke of said last named means.

18. A fuel injector comprising a housing having a fuel chamber therein, said housing having a fuel inlet and a fuel outlet communicating with said chamber, fuel supplied to flow into said inlet and out of said outlet maintaining said chamber substantially filled, a longitudinally compressible, elongated bellows extending lengthwise of said housing and forming a deformable pump chamber therein, said bellows being closely confined throughout its length by and within said housing and being closed at one end, the other end being secured in said housing, said housing having a connection between said pump chamber and fuel chamber for supplying fuel to said pump chamber from said fuel chamber, a normally closed valve controlling said last named connection and opening toward said pump chamber, said housing having a discharge duct communicating with said pump chamber, an outwardly opening spring loaded valve normally closing said discharge duct, and means at the other end of said housing operable to move the closed end of the bellows to cause said bellows to intermittently force fuel from said pump chamber to open said last named valve and pass through said discharge duct, return of said bellows permitting said last named valve to close and causing said first named valve to open to supply fuel from said fuel chamber to said pump chamber, said last named valve having means projecting into said bellows adjacent said closed end of said bellows for mechanical actuation by said closed end in the event said last named valve fails to open by pressure.

19. A fuel injector comprising a housing having a fuel chamber therein, said housing having a fuel

inlet and a fuel outlet communicating with said chamber, fuel supplied to flow into said inlet and out of said outlet maintaining said chamber substantially filled, a longitudinally compressible, elongated bellows extending lengthwise of said housing and forming a deformable pump chamber therein, said bellows being closely confined throughout its length by and within said housing and being closed at one end, the other end being secured in said housing, said housing having a connection between said pump chamber and fuel chamber for supplying fuel to said pump chamber from said fuel chamber, said housing having a discharge duct communicating with said pump chamber, an outwardly opening spring loaded valve normally closing said discharge duct and means at the other end of said housing operable to move the closed end of the bellows to cause said bellows to intermittently force fuel from said pump chamber to open said valve and pass through said discharge duct, said valve having means projecting into said bellows adjacent said closed end of said bellows for mechanical actuation by said closed end in the event said valve fails to open by pressure.

20. A fuel injector comprising a housing having a fuel chamber therein, said housing having a fuel inlet and a fuel outlet communicating with said chamber, fuel supplied to flow into said inlet and out of said outlet maintaining said chamber substantially filled, a longitudinally compressible, elongated bellows extending lengthwise of said housing and forming a deformable pump chamber therein, said bellows being closely confined throughout its length by and within said housing and being closed at one end, the other end being secured in said housing, said housing having a connection between said pump chamber and fuel chamber for supplying fuel to said pump chamber from said fuel chamber, said housing having a discharge duct communicating with said pump chamber, an outwardly opening spring loaded valve normally closing said discharge duct and means at the other end of said housing operable to move the closed end of the bellows to cause said bellows to intermittently force fuel from said pump chamber to open said last named valve and pass through said discharge duct, return of said bellows permitting said last named valve to close and causing said first named valve to open to supply fuel from said fuel chamber to said pump chamber, said last named valve having means projecting into said bellows adjacent said closed end of said bellows for mechanical actuation by said closed end in the event said last named valve fails to open by pressure.

21. A fuel injector comprising a housing having a fuel chamber therein, said housing having a fuel inlet and a fuel outlet communicating with said chamber, fuel supplied to flow into said inlet and out of said outlet maintaining said chamber substantially filled, a longitudinally compressible, elongated bellows extending lengthwise of said housing and forming a deformable pump chamber therein, said bellows being closely confined throughout its length by and within said housing and being closed at one end, the other end being secured in said housing, said housing having a connection between said pump chamber and fuel chamber for supplying fuel to said pump chamber from said fuel chamber, means for supplying fluid pressure to said housing on the side of said bellows opposite to that forming the pump chamber, said housing having a discharge duct communicating with said pump chamber, and means

at the other end of said housing operable to move the closed end of the bellows to cause said bellows to intermittently force fuel from said pump chamber through said discharge duct.

22. A fuel injector comprising a housing having a fuel chamber therein, said housing having a fuel inlet and a fuel outlet communicating with said chamber, fuel supplied to flow into said inlet and out of said outlet maintaining said chamber substantially filled, a longitudinally compressible, 10 elongated bellows extending lengthwise of said housing and forming a deformable pump chamber therein, said bellows being closely confined throughout its length by and within said housing, and being closed at one end, the other end being secured in said housing, said housing having a connection between said pump chamber and fuel chamber for supplying fuel to said pump chamber from said fuel chamber, means for supplying fluid pressure to said housing on the side of said bellows opposite to that forming the pump chamber, a normally closed valve controlling said last named connection and opening toward pump chamber, said housing having a discharge duct communicating with said pump chamber, an outwardly opening spring loaded valve normally closing said discharge duct, and means at the other end of said housing operable to move the closed end of the bellows to cause said bellows to intermittently force fuel from said pump chamber to 20 open said last named valve and pass through said discharge duct, return of said bellows permitting said last named valve to close and causing said first named valve to open to supply fuel from said fuel chamber to said pump chamber.

WILLIAM H. MASHINTER.
